ELECTRIC SWITCH

Albert E. Grant, New York, N. Y., assignor, by
direct and mesne assignments, to Albert T. Otto
& Sons, Inc., New York, N. Y., trustee

Application October 25, 1935, Serial No. 46,648

6 Claims. (Cl. 200—116)

My invention relates to electric switches of the type that are actuated to break a circuit by an overload of current. A principal object of my invention is to provide an improved switch 5 of this character incorporating a novel mechanical movement whereby the movable bridging element of the switch mechanism comprises a cam and is pivoted in a manner to change its fulcrum as it is reset to avoid contact with the switch 10 terminals during the resetting movement. Another object is to provide such a mechanical movement.

My novel switch mechanism may be advantageously embodied in a plug device designed to replace the usual screw type fuse plug. Another object of my invention, therefore, is to provide an improved plug-type switch or circuit breaking device which will automatically and instantly break an overloaded circuit and which may be 15 readily reset to perform its function an indefinite number of times without replacement. A further object is to provide a device of this nature which will be simple in construction, inexpensive to manufacture and which will afford protection 20 to the user against shock when coupling or uncoupling this device in circuit in an ordinary fuse box.

Other and further objects will appear from the following specification.

Referring to the drawings, all of which illustrate the device on a scale larger than actual size:

Figure 1 is an elevational view of a circuit breaking device embodying my improved switch 35 mechanism.

Figure 2 is an elevational view of the device taken at right angles to Figure 1.

Figure 3 is a plan view and

Figure 4 is an inverted plan view of the device. 40 Figures 5 to 10 inclusive are sectional views of the device taken on the lines indicated by their respective figure numbers.

Figure 11 is a schematic view of the movable element of the switch member and the parts 45 supporting it in relation to the terminals which it is adapted to bridge in circuit, and shows the relationship of the parts when the circuit is broken.

Figure 12 is a view similar to Figure 11 showing the relationship of the parts at a middle stage 50 of the resetting operation.

Figure 13 is another similar view showing the relationship of the parts at the final stage of the resetting movement.

Figure 14 is a further view similar to Figure 11

showing the relationship of the parts when the resetting operation has been completed and the spring pressed switch element has snapped into bridging position to complete the circuit.

Figure 15 is a sectional view of the parts comprising the switch mounting, taken on line 15—15 of Figure 12.

Figure 16 is a perspective view of the cammed switch member and integral resetting lever.

Figure 17 is a perspective view of the post on 10 which the switch member is mounted.

Figure 18 is a schematic view illustrating the circuit through the device.

The internal parts of the device are mounted 15 on a base 20 of porcelain or other similar insulating material and are encased by a housing 21 of insulating plastic. The base and the housing are held together in assembled relation by a screw shell contact 23 which is flanged at its lower periphery to engage under a shoulder 22 20 formed on the base. The contact carries flanged integral lugs 24 which extend through slots in the casing wall and are clenched against the inner surface thereof, thereby holding the base and the body portion of the housing permanently 25 assembled.

The walls of the housing at the lower portion thereof are circular and coincide with the upper flanged edge of the base 20. The upper portion of the housing is substantially rectangular or 30 obround to afford flat surfaces 25 on opposite sides of the device whereby it may be conveniently grasped when the device is being inserted or removed from a screw socket. Projecting from the flat sides of the casing intermediate its length 35 are semi-circular flanges 26 which form a protective apron for the fingers of the user when coupling or uncoupling the plug in a fuse box.

Formed and proportioned as above described the housing affords the very convenient grips and 40 apron shield for the fingers and may be readily and advantageously adapted to encase plug parts or fuse parts other than those about to be described.

The upper end of the housing is sealed by a 45 cover 27, is mortised into the housing wall, as shown, and has a slot formed therein at 28 through which the reset button 33 of the switch may project.

The base 20 is recessed inwardly from its side 50 below the shoulder 22 at 29 (see Fig. 6) and a metal strip 30 is secured to the base within the recess and extends over the shoulder 22 to contact firmly with the screw contact 23. The strip 30 is secured in position by the lower end of an 55

eyelet 31, the upper end of which secures a conductor 32 within the casing. The conductor 32 is made of light conducting spring metal, such as phosphor bronze, and extends upwardly within the casing, its upper free end being inwardly bent, substantially as shown, to form a shelf-like switch terminal 33.

The other switch terminal 34 consists of the angularly bent free end of a bi-metallic conductor 35. This latter conductor comprises a thermostat and its lower bent end is secured by an eyelet 36 in a pocket 20' formed in the base 20. The eyelet 36 also secures the lower end of a heating element 37 in firm contacting relation with the thermostat.

The heating element is composed of resistance wire, such as nichrome alloy, which is wound in flat coils extending parallel and in close adjacency to the thermostat and to a wall 40 projecting upwardly from the top of the base 20 into the housing. The upper end of the heating element is secured to the upper end of a central contact member 38 which extends through the base and projects exteriorly thereof at 38'.

The switch terminals are adapted to be bridged by a spring pressed element 51 which is supported by the bi-metal terminal 34 and contacts against the light resilient shelf-like terminal 33. It will therefore be apparent that the circuit through the plug will pass through contact 38, traverse the heating element and thermostat to the terminal 34, thence across the switch bridge 51 to the terminal 33 from which it will be carried by the conductor 32 to strip 30 and the screw contact 23.

The gauge or capacity of the resistance wire forming the heating element is sufficient to conduct the maximum load desired without generating any appreciable heat. When the circuit is overloaded, however, the element heats rapidly and the heat so generated radiates against the adjacent side of the thermostat. The heat is also reflected against the thermostat by the walls of the pocket 20' and by the wall 40, causing the bi-metal to warp away from its supporting position under the spring pressed switch member whereupon the switch member will deflect the light terminal 33 out of its path and drop from its bridging position.

The switch mechanism is mounted on a strip support 42 secured to the base 20 by eyelet 43. The upper end of the support is of reduced breadth and angularly bent to form an arm 44. Below the arm and extending parallel thereto the support carries a transverse pivot post 45 on which the moving parts of the switch mechanism are rotatably mounted (see Fig. 15). Separated from the support by a washer 46 is a switch member 50, formed, as shown in Figure 16, to comprise a bridging element 51 at one end and a lever 52 projecting angularly from the other end thereof for manually setting or resetting the switch, the end of the lever being capped by a rounded button 53 fused or otherwise secured thereto.

The switch member is slotted intermediate its length at 54 whereby it is pivotally and slidably mounted on the post and its edge is contoured to define a double cam, being cams 55 and 56 respectively, the latter being formed in the angle defined by the projecting lever portion 52 and both being positioned and adapted to ride against arm 44.

Mounted on the post outwardly of the switch member is a sleeve 58 having its inner end flanged

to form a seat for the innermost convolution of torsion spring 60, the outer end of which is anchored to a horseshoe nut 61 pinched around the post adjacent its end, the post being slotted to receive the nut as shown (Figure 15).

The inner end of the torsion spring 60 is extended from the coil to form a spring finger 65 overlying the bridging element 51 whereby the element is urged downwardly at all times, tending to pivot the switch member about the post 45 with the end margins of the slot 54 nearest the switch terminals in engagement with the pivot post, as shown in Figure 11.

To set or reset the switch, the button 53 is wiped downwardly sidewise from its projecting position above the cover 27 (Figures 1-3) until it is substantially flush therewith, whereupon the finger of the user will be caused to slip from its engaging position. The first stage of this movement is a simple pivot causing the bridging element to swing upwardly above the terminals 33 and 34 in spaced relation thereto, until the cammed edge 56 of the switch member engages the arm 44, as shown in Figure 12. During the second stage of the pivoting movement the cam 56 rides against the arm and the member is thereby caused to walk bodily in the direction of the terminals, sliding to change its fulcruming point to the opposite end margins of the slot and assuming the position indicated in Figure 13. The finger of the user then releases the actuator button and the member is forced to move in a reverse direction by the spring 60, this reverse movement being a simple pivot which is interrupted when the element 51 snaps into bridging contact on the switch terminals to complete the circuit, as indicated in Figure 14.

In operation, whenever an overload of current causes the element 37 to generate any appreciable heat, such heat radiates and is reflected against the side of the thermostat most closely adjacent, causing the bi-metal to be deflected from its supporting position under the bridging element thereby releasing the switch member which is snapped downwardly by the spring, brushing the light resilient terminal 33 out of its path and breaking the circuit.

In an early stage of this circuit breaking movement, the cam 55 rides against the arm 44 and the switch member is thereby caused to slide bodily in a direction away from the terminals, changing its fulcruming point to the opposite end margins of the slot where it continues to pivot until the bridging element 51 strikes against the support 42 and takes the position indicated in Figure 11. Figure 11 clearly indicates the paths traversed by the bridging element in its movements.

When the short circuit or other trouble causing the overload has been remedied and the thermostat has cooled sufficiently to resume its normal position, the switch may be reset, as heretofore described, to complete the circuit again. In this manner the device may be used in place of the usual fuse plug and will serve to protect the circuit a large and indeterminate number of times.

It will be noted that practically no strain whatever is placed upon the bi-metallic thermostat conductor which operates merely as a trip for the switch and not as an actuator therefor.

The pivoting switch mechanism embodying the double cam and link mounting is believed to comprise an entirely novel mechanical movement, independently useful whenever it may be desired to

provide a member adapted to pivot through different paths in opposite directions.

The foregoing description taken in connection with the accompanying drawings discloses the principles of a switch mechanism and of a circuit breaking device which will be readily understood by those skilled in the art to which the invention appertains and comprises what I now consider to be the best embodiment thereof. I desire to have it understood, however, that the structure shown is merely illustrative and that such changes and adaptations may be made, when desired, as fall within the scope of the here appended claims.

I claim:

1. A screw plug of the character described comprising a casing and contacts carried thereby exteriorly thereof, a bi-metallic thermostat within the casing, a switch terminal carried by said thermostat, means within the casing connecting said contacts in circuit, said means comprising said thermostat, a stationary heating element and a switch member supported by said terminal; the arrangement being such that heat generated by said element will be radiated and directly reflected by the walls of the pocket against the thermostat and cause the thermostat to deflect and move said terminal from its supporting position to release the switch and break the circuit.
2. A screw plug of the character described comprising a casing having a body portion and contacts carried by the body portion exteriorly thereof, said body portion having a pocket formed in an interior wall thereof, a bi-metallic thermostat within the casing having one end secured in said pocket and a switch terminal carried by the thermostat at its other end, means within the casing connecting said contacts in circuit, said means comprising a switch member supported by said terminal and a heating element located in close adjacency to the thermostat in said pocket, the arrangement being such that heat generated by said element is radiated and directly reflected against the thermostat by the walls of said pocket, causing the thermostat to deflect and move said terminal from its switch supporting position to release the switch and break the circuit.
3. A screw plug of the character described comprising a casing and contacts carried thereby exteriorly thereof, a thermostat within the casing, means within the casing connecting said contacts in circuit, said means comprising a

spring pressed switch and a heating element, said element being located in close adjacency to said thermostat, and means operable by the thermostat for releasing the switch to break said circuit; said switch comprising a pivoting member having a slot formed therein, a support affording an axis on which the slotted portion of the member is slidably and pivotally mounted, a spring urging the member to pivot in the direction of contact, a cam carried by the member, and a fixed cam riding element for engagement by the cam, said cam being contoured to guide the member in a sliding movement on its axis as it is pivoted thereon, whereby the member contacts the terminals when it is pivoted in one direction and avoids them when it is reverse-ly pivoted.

4. A pivot mechanism comprising a pivoting member having a slot formed therein, a support affording an axis on which the slotted portion of the member is slidably and pivotally mounted, a cam carried by the member, and a fixed cam riding element for engagement by the cam, said cam being contoured to guide the member in a sliding movement on its axis as it is pivoted thereon.

5. A pivot mechanism comprising a pivoting member having a slot formed therein, a support affording an axis on which the slotted portion of the member is slidably and pivotally mounted, resilient means urging the member to pivot in one direction, a cam carried by the member, and a fixed cam riding element for engagement by the cam, said cam being contoured to guide the member in a sliding movement on its axis as it is pivoted thereon.

6. A screw plug of the character described comprising a casing and contacts carried thereby exteriorly thereof, means within the casing connecting said contacts in circuit, said means comprising a thermostat and a switch operable by the thermostat, said switch comprising a pivoting member having a slot formed therein, a support affording an axis on which the slotted portion of the member is slidably and pivotally mounted, a cam carried by the pivoting member, and a fixed cam riding element for engagement by the cam, said cam being contoured to guide the member in a sliding movement on its axis as it is pivoted thereon, whereby the member is caused to make contact when pivoted in one direction and to avoid contact when reverse-ly pivoted to reset the switch.

ALBERT E. GRANT.
